ILLUMINABLE DISPLAY BOX FOR PHOTOGRAPHIC TRANSPARENCIES

Levi C. Chapiewsky, 116 Commercial St., Bangor, Wis.

Filed July 10, 1962, Ser. No. 70,863

Term of patent 7 years

(Cl. D29—20)

FIG. 2

FIGURE 1 is a side elevational view of an illuminable display box for photographic transparencies showing my new design, the box is symmetrical and the other three sides are similar in appearance to the side shown;

I claim:

The ornamental design for an illuminable display box for photographic transparencies, as shown and described.
